SPINNING PROCESS AND APPARATUS
THEREFOR

Paul Pierrat and Eugene Colombu, Paris, France,
assignors, by mesme assignments, to E. I. du
Pont de Nemours & Company, Wilmington,
Del., a corporation of Delaware

Application September 7, 1934, Serial No. 743,105

3 Claims. (Cl. 117—27.6)

This invention relates to a process of collecting yarn such as freshly formed artificial silk yarn in a centrifugal spinning bucket and to means for traversing the funnel that guides the 5 yarn, thread or like material into the rotating bucket.

The customary manner of spinning and collecting artificial silk thread such as is produced by the viscose process in a centrifugal bucket comprises directing the thread into the bucket through a funnel mounted for vertical reciprocation to distribute the thread between top and bottom of the bucket, which motion in combination with the turning of the bucket causes the 10 thread to be deposited in the bucket to form a cross wound package, or what is termed a "cake" of yarn. The reciprocation of the funnel is at a constant rate and at some stage of the building 15 of the cake, the movement of the funnel and the circumferential size of the cake are such that a thread is deposited adjacent and parallel to previous courses to form bands or ribbons. These bands will vary in width according 20 to the ratio between the funnel movement and the circumferential size of the cake and at times may be of considerable width. As a result, the cake does not well retain its structure during processing and it will not lend itself to uniform treatment. Furthermore, when the 25 thread is unwound therefrom, it is apt to sluff or slide off where ribbons occur in a large mass, to tangle and to cause excessive waste.

It has been proposed (German Patent No. 552,470) in order to produce firm cakes which 30 are not easily collapsed, to periodically change the angle of intersection between different thread windings. The changing angle of intersection of the thread is brought about by changing the form of the cam which causes the funnel guide 35 to rise and fall at varying rates of speed. The changes in speed of the funnel guide are within one or two strokes, and at some point in the spinning of the cake there will be formed in the cake bands or ribbons such as are formed in the 40 usual method of spinning bucket cakes and the objections of sluffing and excessive waste, broken threads, etc. as with other prior art are not overcome.

It is therefore an object of our invention to 45 provide a method and means for centrifugally winding thread in the form of a cake of improved compactness and free from band or ribbon formation. Other objects will be apparent from the description that follows.

50 Referring to the drawing in which like refer-

ence characteristics designate like parts throughout: Figs. 1, 2 and 3 are diagrammatic views of various thread traverse control assemblies.

It has been discovered, in accordance with the present invention, that band or ribbon formation in the centrifugal spinning of artificial thread, can be avoided by varying the rate of reciprocation of the traverse funnel through which the thread is led into the centrifugal bucket in such a way that there is no substantial coincidence 5 or repetition in the laying down of the thread. In its preferred form, this variation in thread traverse is accomplished by slowly changing the speed of the cam shaft which operates the funnel traverse mechanism. In the drawing, various 10 alternative means for accomplishing this result are shown, but it is to be understood that the preferred form is illustrated in Figure 1.

Referring to Figure 1, 1 is the driving shaft 20 which may or may not be the main drive shaft of the spinning machine. Attached to it is pinion 2 gearing with pinion 3 on shaft 4. The latter drives shaft 6 by means of oppositely disposed conical pulleys 5—A and 5—B and belt 5 as shown. Shaft 6, in turn, drives shaft 9 to 25 which is fastened cam 10. Pinions 7 and 8 fixed to shafts 6 and 9 respectively are for this purpose. Belt 5 passes between the fingers of a fork 5—C attached to a ring 14 which slides without revolving on a shaft 13 supplied with both 30 left- and right-hand screw threads. Shaft 13 and shaft 12 to which it is attached are revolved by means of gears 11—A and 11—B and shaft 4. Suitable projections fastened to ring 14 running in the grooves of the left- and right-hand 35 threaded member cause the belt to be shifted continuously one way and then the other as the ring 14 travels from one end to the other of the threaded portion of member 13.

The rapidity of the change in funnel speed 40 may be regulated, of course, in many ways, for instance, by changing the pitch of the cone pulleys, the pitch of the threads or the length of the threaded portion on member 13, or by changing the size of gears 11—A and 11—B.

45 With the arrangement just described and shown in Figure 1 of the drawing, the cycle which comprises the travel of the belt 5 from one extreme position, for example, at the left, to the other extreme position and back again, will be 50 very slow and will preferably cover that period within which the funnel guide takes at least 100 strokes. It will be understood that this cycle may cover a period of several hundred strokes, or for that matter, even less than 100 strokes of 55

the funnel guide. As further illustration of means for varying the speed of the funnel guide in a manner similar to that just described, reference is made to the diagrammatic systems shown in Figures 2 and 3.

In Figure 2, 20 is a main drive motor which serves only for the funnel traverse motion in the spinning machine. This motor is a variable speed motor and is controlled by a variable resistance 21 through a gear train 22, 23, shaft 24 and gears 25 and 26 driven from the motor shaft 27 as shown. Cam 32 is fixed to gear 31 and by means of a gear train 28, 29 and 30 connecting with gear 31, the main shaft 27 of the motor causes cam 32 to revolve. Cam 32 operates the funnel traverse bar and the funnel guide mounted thereon through the traverse bar lifter rod 34 and suitable linkage 35, 36, 37 and 38 illustrated diagrammatically, the funnel guide being reciprocated at constantly varying rates of the same character as described in connection with Figure 1.

In Figure 3 a set-up similar to that just described is shown, but instead of using a variable speed motor, a constant speed motor may be used and the cam driven through a suitable gear train 40, 41, 42 and 43 that is connected to the motor through a variable speed drive 44 such as a drive of the Reeves or a PIV type having a suitable variable speed control box 45.

A conventional traverse bar 50 with an accompanying funnel guide 51 has been shown connected to the lifter rod 34. The funnel guide 51 is shown projecting into a spinning pot in a known manner.

From the description given above of the various means for producing the desired results, it is to be noted that the change in funnel speed takes place very slowly. In other words, there 40 is no perceptible change from one stroke to another, nor within the stroke. It is preferred that the change takes place within a cycle which comprises from 100 to 1000 or more strokes of the guide funnel, which change will not appreciably alter the shape of the cake or appreciably change the angle at which various adjacent layers of the threads cross, but which will prevent synchronism between the movement of the funnel and the rotation of the bucket and thereby pre-

vent formation of bands or ribbons in the cake.

The cakes produced according to our invention are well formed and of uniform compactness. They can be processed easily and uniformly by any of the customary methods for fluid treatment of cakes and the yarn can be unwound therefrom with substantially no waste.

While the invention has been described in its application to the production of regenerated cellulose thread or the like produced from viscose, 10 it is equally applicable to any centrifugal spinning process such as for instance the spinning of cuprammonium cellulose threads, or other cellulose derivative threads or to textile threads of any description that are collected in rotating 15 buckets as cross-wound cakes.

We claim:

1. In an apparatus for regulating the speed of traverse of the funnel through which artificial thread is led into a spinning bucket in a centrifugal spinning process, means for imparting to the funnel reciprocating motion, means for supplying energy to said first named means from an outside source of power, and means intermediate said before mentioned means which constantly changes the speed of said first mentioned means for a period covering at least fifty strokes of said funnel.

2. In an apparatus for regulating the speed of traverse of the funnel through which artificial thread is led into a spinning bucket in the centrifugal spinning process, means connected with the funnel for imparting a traverse motion thereto, a rotating cam shaft having a cam mounted thereon for imparting motion to the said means, means for supplying energy to the said cam shaft in order to rotate the same, and means intermediate the cam shaft and the last mentioned means which continuously and slowly changes the speed 30 of the cam shaft.

3. Apparatus as claimed in claim 2 in which the said intermediate means for varying the speed of the cam shaft comprises a pulley driving a belt which in turn drives another pulley which is connected with the cam shaft, such 45 pulleys being frusto-conical in form and inverted with respect to each other.
